Patented Apr. 6, 1920.

Inventor
John Johnson,

By his attorneys

Edgar Gate & Co.

UNITED STATES PATENT OFFICE.

JOHN JOHNSON, OF NEW YORK, N. Y.

DOOR.

1,335,838.

Specification of Letters Patent.

Patented Apr. 6, 1920.

Application filed March 16, 1918. Serial No. 222,791.

To all whom it may concern:

Be it known that I, JOHN JOHNSON, a citizen of the United States, and residing at New York, in the county of Bronx and 5 State of New York, have invented certain new and useful Improvements in Doors, of which the following is a specification, such as will enable those skilled in the art to which it appertains to make and use the 10 same.

This invention relates to doors and particularly constructions of this class designed for use in connection with booths, cabinets, closets and the like and to what are known 15 as telephone booths, and the object of the invention is to provide an improved construction of this character with improved means for operating the same, and a further object of the invention is to provide a simple, efficient and practical door construction of the class and for the purpose specified. 20

The invention is fully disclosed in the following specification, of which the accompanying drawing forms a part, in which the 25 separate parts of my improvement are designated by suitable reference characters in each of the views, and in which:—

Figure 1 is a front view of a telephone 30 booth showing my improved door connected therewith and in a closed position;

Fig. 2 a section on the line 2—2 of Fig. 1 and on an enlarged scale showing my improved door closed in full lines and indicating the same open in dotted lines; and, 35

Fig. 3 a partial section on the line 3—3 of Fig. 1 and showing means for holding my improved door in a closed position.

In the drawing 5 is a telephone booth comprising a back wall 6, side wall 7, a bottom 8 and a top 9, all of which parts are connected in the usual or any desired manner. It will be noted on a careful consideration of Figs. 1 and 2 that the front edge of the top and bottom of the booth is formed into a front face 10 having angular and oppositely directed faces 11, which join the front edge portions of the sides 7 of the booth, as clearly indicated in Fig. 2 of the drawing, and the 45 inner faces of the sides 7 of the booth are provided adjacent to the front edges thereof with arc-shaped recesses 12, as clearly shown in Fig. 2.

Pivotedly mounted between the top and 50 bottom of the booth as indicated at 13 in Fig. 2 is my improved door construction 14,

comprising three approximately similar door members 15, 16, and 17. The door member 15 is pivoted to the booth, as shown at 13, while the door member 16 is pivoted to the door member 15 as shown at 18 and the door member 17 is pivoted to the door member 16 as shown at 19, and the outer edge portions of the door members 15 and 17 are rounded as shown at 20 and are adapted 60 to operate in the recesses 12 to seal or provide a tight connection of said door members with the sides 7 of the booth. 65

The door members 15, 16 and 17 are paneled below the center thereof, as indicated at 21 in Fig. 1, and provided with glass panels 22 above the center thereof, and the door members 15 and 16 are jointed as shown at 23 in Fig. 2, while the door members 16 and 17 are similarly jointed as 70 shown at 24 in said figure, and the joints 23 and 24 combined with the rounded edges 20 on the door members 15 and 17 serve to close the booth 5, or prevent sound from freely passing into or out from said booth. 75

It will be noted that the door, or the separate members thereof, when in the closed position conform to the front portion of the top and bottom of the booth, or the central door member 16 is arranged in a plan parallel with the back of the booth, while the door members 15 and 17 incline backwardly at the opposite sides, and this angular arrangement of the separate members of the door improve the appearance of the booth 85 and also increase the capacity thereof, as will be readily understood, and by the specific arrangement of the separate members of the door, said door is provided with a free or easy action in the operation of opening and closing the same. 90

The door 14, or the separate members thereof, are operated by rods 25 and 26, the rod 25 being pivoted to the top 9 of the booth as shown at 27, and to the inner face 100 of the door member 17 as shown at 28 adjacent to the connection of said door member with the member 16, while the rod 26 is pivoted to the top 9 of the booth as shown at 29, and to the inner face of the door member 17 adjacent to the free edge thereof, as shown at 30, and connected with the rods 25 and 26 adjacent to their pivots at 27—29 respectively as shown at 31 are coil springs 32 which are also secured to the top 9 of the booth as shown at 33, and these springs 105 serve to hold the separate members of the 110

door 14 in their open position, or the position indicated in dotted lines in Fig. 2, but when it is desired to use the booth, the separate members of the door are swung into the 5 full line position shown in Fig. 2 and may be locked in such position by any suitable lock device, but in Fig. 3 of the drawing I have shown at 34 a device of this class of the hook and eye form, it will be understood 10 that when it is desired to vacate the booth by simply releasing the lock device 34 the separate members of the door will be thrown open automatically by the springs 32.

15 The springs 32, as above stated, normally serve to hold the door in its open position, and said door is closed and locked in its closed position against the tension of said springs, and while I have shown the springs 20 32 connected with the rods 25 and 26, it will be understood that the hinges at 18 and 19 may be spring hinges and a coil spring may be connected with the pivots at 13 to accomplish the same result as said springs 25 32, and changes in an modifications of the details of construction herein shown and described may be made, within the scope of the appended claims, without departing from the spirit of my invention or sacrificing 30 its advantages.

Having fully described my invention, what I claim as new and desire to secure by Letters Patent, is:—

1. The combination with a booth having 35 a door opening, of a three-section door hav-

ing one of its sections hinged to the door jamb, the free section folding upon the intermediate one and the latter upon the section which is hinged to the door jamb, rods pivotally connected to the door and to said 40 booth for controlling the door sections and causing one section to fold upon the intermediate section and the intermediate section to fold upon the jamb section when the door is opened, and springs for automatically 45 opening the door.

2. The combination with a booth having a door opening, of a folding door mounted in said opening and comprising three sections hinged together, one of said sections 50 being hinged to the door jamb of the booth, and rods having certain of their ends connected to the door and their other ends connected to fixed points, said rods controlling the folding of the door and causing one of 55 the sections to fold onto another section and that section to fold onto the remaining section when the door is opened.

3. A combination as defined in claim 2, in which the rods are crossed and connected to 60 only one of said sections.

In testimony that I claim the foregoing as my invention I have signed my name in presence of the subscribing witnesses this 14th day of March, 1918.

JOHN JOHNSON.
